HUGH A. DEEKS, OF MOOSE JAW, SASKATCHEWAN, CANADA.

MEANS FOR FILTERING GASOLINE.

1,427,196.

Specification of Letters Patent. Patented Aug. 29, 1922.

Application filed January 31, 1920. Serial No. 355,492.

To all whom it may concern:

Be it known that I, HUGH A. DEEKS, a subject of the King of Great Britain, residing at Moose Jaw, Province of Saskatchewan, Dominion of Canada, have invented certain new and useful Improvements in Means for Filtering Gasoline, of which the following is a specification.

This invention relates to improvements in means for filtering gasoline, pertaining more particularly to devices interposed between a gasoline storage tank and the point of use, such for instance as a carburetor of a motor vehicle, the means thus acting as an automatic cleansing device capable of supplying the carburetor with clean fuel.

While many and varied attempts have been made to produce this result, these attempts have been more or less unsatisfactory. For instance, structures capable of good filtering action have been more or less difficult to cleanse from the impurities, requiring complete disassembly of parts and the use of expert labor in restoring the filter to satisfactory working condition; furthermore, the time and labor required in providing this result are such as to produce a serious factor in the use of devices of this type, it being necessary to place the motor vehicle out of service for considerable periods owing to the necessity of securing such expert assistance. Other types provide inefficient cleansing action on the gasoline content, while in some cases, the arrangements are such as to produce rapid clogging of the filtering structure, thus necessitating frequent cleansing. Owing to the fact that these difficulties are of lesser degree than those produced by employing an uncleansed gasoline in the motor, these devices have been employed in spite of their disadvantageous formations.

The present invention is designed to meet these different conditions by producing a construction which is efficient in the cleansing of the gasoline content, which is so arranged as to provide the filtering action with a minimum amount of clogging possibility, and in which the filtering structure is so arranged as to permit of ready removal and cleansing without requiring skilled labor in producing the result, the structure having "fool-proof" characteristics which enable an unskilled workman to take down and re-assemble the structure without liability of error.

Other objects are to provide means for the purpose which are simple and efficient in operation, durable in construction, and which can be manufactured and installed at a relatively low cost.

To these and other ends, therefore, the nature of which will be readily understood as the invention is hereinafter disclosed, said invention consists in the improved construction and combination of parts hereinafter fully described, illustrated in the accompanying drawings, and more particularly pointed out in the appended claims.

In the accompanying drawings, in which similar reference characters indicate similar parts in each of the views,—

Figure 1 is a vertical sectional view taken centrally through a device forming one embodiment of the general invention.

Fig. 2 is a rear elevation of the same—the view looking toward the outlet end of the device.

Fig. 3 is a view, partly in section and partly in elevation, showing the removable unit of the device.

Fig. 4 is a fragmentary sectional view of the filter unit.

The means preferably employed in carrying out the general principles of the present invention, is in the form of two connected elements *a* and *b*, these, in assembled relation completing the filter structure, removal of element *b* bodily, as a unit, exposing the interior of element *a* and rendering accessible the filtering unit, indicated generally at *c*.

Element *a* is the form of casing 10 having an open side, the casing being preferably approximately cylindrical in form with respect to its open side, the axis of the cylinder being inclined to the horizontal under service conditions, the inclination being approximately equal to an angle of 22°; this places the plane of the open side of equal angularity to the vertical, and since the closed end of the element is formed by a side 10^a which extends substantially vertically when the device is properly mounted, it will be understood that the two planes corresponding to the opposite ends of this cylindrical portion are inclined relatively to each other. As a result, the cup-shaped interior of element *a* is of greater depth at its lower portion—the wall joining the cylindrical and end walls being preferably curved as shown—this portion forming a pocket for

all sediment collections, since the walls of the cylindrical portion incline upwardly relatively to the bottom of the pocket. A suitable plug valve or cock 11 is located at 5 such lower pocket end, permitting ready removal of the collections.

12 designates a connection nipple or other suitable form of connecting element by means of which the device can be connected 10 up within the gasoline line of the motor vehicle, nipple 12 being preferably connected to the feed line from the storage tank and opening into the interior of the casing adjacent its top.

15 The casing is mounted in suitable manner on the motor vehicle, a preferred arrangement being by the use of a flat securing member 13, threaded to the upper end of the casing, and locked in position by a lock nut 20 13^a, this arrangement permitting the casing to be accommodated relative to a convenient part of the vehicle—such part itself extending in a vertical plane—so that wall 10^a will extend substantially vertical when 25 in position.

Element *b* is a removable element which forms a closure for the open end of the casing. Element *b* includes a plate-like member 14 and in annular flange 14^a, the latter 30 carrying external threads 14^b which are adapted to be threaded to complementary internal threads at the open end of the casing. Flange 14^a extends inwardly into the casing a distance beyond the threaded 35 connection, and has its inner end internally threaded, as at 14^c in advance of an annular shoulder 14^d, said shoulder forming a seat for the filter unit, presently described, the unit being held to its seat by an annular 40 threaded clamping member 15 which cooperates with threads 14^c and which may be provided with depressions 15^a to facilitate threading and unthreading movements.

Member 14 carries the discharge nipple 16, 45 the latter being connected up to the line leading to the carburetor—or to the vacuum tank, if the filter is employed in such service.

The filter unit *c*—a portion of which is shown in Fig. 4 on enlarged scale—comprises an annular member 17, preferably of 50 metal, and somewhat conical in section diametrically, one end being formed with an outwardly projecting flange 17^a, adapted to seat on shoulder 14^d, the opposite end being 55 preferably provided with a shoulder or other formation, indicated at 17^b, the particular shape of this part 17^b being illustrative of different shapes which may be employed.

The filter is in the form of two spaced- 60 apart filtering mediums. 18 designates the advance medium, this being in the form of wire gauze of fine mesh secured in suitable manner to the face of flange 17^a; if desired, the member 18 may be soldered or brazed 65 to the flange, it being desired that this mem-

ber be not separated from member 17 when the parts are removed for cleaning.

The second filter medium is preferably in the form of a multi-ply construction which includes a layer of chamois 19 and a fabric layer of different material and indicated at 70 20; the material I prefer to employ is silk although other materials having similar characteristics to silk in the smoothness of texture, may be employed.

The two layers overlie the opposite end of member 17 and extend over the configuration 17^b, being held in position by a suitable retainer, such as wire 21 which cooperates with shoulder 17^b in retaining the 75 80 multi-ply structure in proper position.

As will be understood, member 17 and the parts carried thereby are held in position by the clamping action of member 15, removal of the latter permitting the unit *c* 85 to drop out of the cover element *b*. And when unit *c* is released, it is necessary only to remove the holding means 21 to permit the multi-ply formation to be removed for cleansing, leaving medium 18 exposed on 90 its opposite sides, and opening the interior of member 17 to free cleaning action. It is necessary only to replace the plies 19 and 20 and secure them with the retaining member 21—an operation requiring no skilled 95 labor—thus completing unit *c*; then inserting unit *c* into position in member 14, and threading member 15, to position, completing unit *b*—both operations being had while member 14 is separate from 100 the casing and therefore readily handled; after which unit *b* is inserted into the casing and threaded to position, thus completing the device.

I prefer to employ a ply in addition to 105 the chamois ply 10, for the reason that all chamois has a more or less rough surface, so that any sediment which would pass through the screen 18 into contact with the second filter would, if chamois alone were to be 110 employed, be likely to adhere to the surface of the chamois. To obviate this I employ the second layer of fabric 20, this being placed in position in advance of the chamois layer, so that the fabric layer forms 115 a protecting shield for the chamois layer, and at the same time permits free access to the chamois of all solution content. By the use of silk the smooth finish offers no material conditions for the adherence of sediment 120 collections, so that there is a tendency of the multi-ply formation to "shed" itself of such sediment collections and thus reduce 125 the tendency to clog the filter.

This ability of the filter unit to "shed" 125 the sediment is not only produced by the use of the smooth fabric material, but by reason of the angularity of the filtering surfaces to the vertical, the lines of divergence from the vertical increasing from the 130

upper end of the receiving chamber—the casing interior—toward the bottom of the chamber formed by the enlarged pocket. As a result, the sediment intercepted by the 5 two filter surfaces can move by gravity away from a lower portion of the surface and toward the pocket—either the main pocket adjacent the drain outlet, or the lower portion of the space between the filter surfaces 10 —so that there is a constant tendency of the surfaces to cleanse themselves from the collected sediment, leaving a large and free surface exposure to the surfaces. And the same is true with the collection of water 15 which may be provided by the action of the chamois ply, this collecting at the bottom of the space between the surfaces, and since the flange 17^a is approximately equal to the thickness of member 15, it will be understood 20 that the collected water will simply pass through the screen 18 into the main pocket adjacent the draining valve through which it can be drained at intervals.

As will be understood, it is only necessary 25 to disconnect nipple 16 from the outlet line—a suitable union may be employed to permit of this being readily done—whereupon unit *b* can be bodily removed, thus exposing the entire interior of the casing to permit 30 thorough cleansing of the casing and units *b* and *c*, the casing remaining undisturbed. And since unit *b* is secured in position by threading action, no particular care is required in restoring the units to position, 35 thus making it unnecessary to employ skilled labor to produce the cleansing operation. And since all filtering surfaces are removed with the removal of unit *b* and then of unit *c*—the removal of the two-ply 40 formation giving access to opposite sides of the secured surface 18—the entire structure is capable of being thoroughly cleansed in a most convenient manner.

As will be understood that arrangement 45 employs but few parts having configurations which can be produced in a simple manner, and all of which are of such character as to practically eliminate liability of loss of parts during the disassembled period. This permits of a comparatively low cost of production, and since the arrangement provides for housing of filtering surfaces, there is little liability of damage to the surfaces during handling or in use.

50 The arrangement is such as to permit its production in comparatively large sizes. For instance, in practice, the screen 18 has an exposed diameter of approximately three and one half inches, with the result that a 55 large surface exposure is had permitting continued use for extended periods without cleansing, and making it possible to produce a practically standard size for most of the 60 size motors now in general service. In addition, the structure is compact and of a con-

figuration not liable to damage or accumulation of external accretions, since there is an absence of nooks and corners which could serve as collecting points and which would tend to permit dripping into the interior. 70

While I have herein shown and described a preferred arrangement and construction, it will be readily understood that changes or modifications therein may be found desirable or essential in meeting the various exigencies of use, and I desire to be understood as reserving the right to make any and all such changes or modifications as may be found desirable or necessary in so far as the 80 same may fall within the spirit and scope of the invention as expressed in the accompanying claims when broadly construed.

Having thus described my invention, what 85 I claim as new is:

1. In means for filtering gasoline, a casing having an end-wall adapted to extend in an approximately vertical plane and having its opposite end open with the plane of the open end inclined to such end wall, and 90 with the direction of increase in distance between such planes extending toward the bottom of the casing, and a removable unit mounted within and closing such open end, said end wall and said unit respectively carrying the inlet and outlet for gasoline, said unit carrying successive filter media between such inlet and outlet with the several media extending in spaced-apart planes substantially parallel to the plane of the casing open 95 end.

2. In means for filtering gasoline, a casing having an end wall adapted to extend in an approximately vertical plane and having its opposite end open with the plane of 100 the open end inclined to such end wall, said open end having its walls of substantially circular contour with the interior threaded, the direction of increase in distance between the planes of the end wall and of such open 110 end extending toward the bottom of the casing, whereby the axis of such open end is inclined to the horizontal with the direction of inclination leading away from such end wall, and a removable unit threaded into 115 and closing said open end, said end wall and unit respectively carrying the inlet and outlet for the gasoline, said unit carrying successive filter media between said inlet and outlet with the several media extending in 120 spaced apart planes substantially parallel to the plane of such open end of the casing.

3. Means as in claim 2 characterized in that the inlet is located adjacent the top of the chamber which is in advance of the filter 125 media with the lower portion of the chamber forming a drainage pocket having a controllable outlet.

4. In means for filtering gasoline, a casing having an open end, a removable closure 130

unit for such open end, said closure unit having an annular flange extending into the casing and carrying a seat for a removable filter unit, whereby the filter unit is bodily removable with the closure unit, and means carried by the closure unit for clamping the filter unit to its seat, said casing carrying the inlet and said closure unit the outlet for the gasoline, said closure unit being positioned to locate the filter unit as an inclined wall of a receiving chamber for the unfiltered gasoline with the chamber decreasing in width toward its upper end.

5. In means for filtering gasoline, a device formed of an assembly of units arranged to locate a succession of filter media between the inlet and outlet for the gasoline into and out of the device, said assembly comprising a casing, a detachable closure unit and a filter unit, said filter unit being carried by the closure unit and detachable bodily therefrom when the closure unit is removed from the casing, said units having their axes inclined to the horizontal when in the assembly position, whereby the filter media will extend in planes inclined to the vertical, the direction of inclination of such media planes locating the bottoms of the media an increased distance from the vertical plane of the casing as compared to that of the tops of the media.

6. In means for filtering gasoline, a device formed of an assembly of units arranged to locate a succession of media varying as to

filtering characteristic between the inlet and outlet for the gasoline into and out of the device, said assembly comprising a casing, a closure unit and a filter unit, said closure and filter units having corresponding axes and positionable relative to the casing with the axes inclined to the horizontal to place the planes of the respective media inclined to the vertical, said closure unit forming the sole support of the filter unit, the latter unit being bodily removable from the closure unit when the latter is removed from the casing.

7. In means for filtering gasoline and wherein the means is formed of an assembly of elements arranged to locate a succession of filter media within the device between the gasoline inlet and outlet thereof, and wherein the assembly includes an open-ended cup-shaped casing into which the gasoline is delivered, a combined closure and media-carrying unit detachably engaging the casing with the unit axis located to position the media in planes inclined to the vertical toward the bottom of the casing, the gasoline outlet being carried by the closure and having its axis extending normal to the media planes.

In testimony whereof, I have affixed my signature in the presence of two witnesses.

HUGH A. DEEKS.
